STONE ASSEMBLY FOR HONING TOOLS

Original Filed May 3, 1940

UNITED STATES PATENT OFFICE

2,436,215

STONE ASSEMBLY FOR HONING TOOLS

John E. Kline, Grosse Pointe Farms, Mich., assignor to Micromatic Hone Corporation, Detroit, Mich., a corporation of Michigan

Original application May 3, 1940, Serial No. 333,195, now Patent No. 2,349,628, dated May 23, 1944. Divided and this application May 19, 1943, Serial No. 487,560

5 Claims. (Cl. 51—204)

1

My invention relates to honing tools, and particularly to a honing stone employed in a tool of the external type which accurately machines the external surfaces of cylindrical elements parallel to its axis and is a division of application, Serial No. 333,195, filed May 3, 1940 and which issued as Patent No. 2,349,628 on May 23, 1944.

In my co-pending application, which issued into Patent No. 2,313,442 on March 9, 1943, I have illustrated an internal type of tool for accurately honing internal surfaces, the claims of which were drawn of a breadth to also cover external type of honing. In this disclosure, a tool was provided having a honing head comprising a plurality of honing stones having extended in indented portions which nest with each other to provide a continuous circumferential abrasive surface so that a final operation may be performed in reciprocation only to provide finish marks throughout the cylindrical surface of the workpiece which are parallel to the axis thereof. This finish simulates the finish on internal or external cylindrical surface which have been in operation over a considerable period of time. Such a finish produced by a honing tool eliminates the friction and resulting heat and the resulting damage which occurs during the "running in" operation of reciprocating cylindrical surfaces.

The present invention contemplates the use of diagonally disposed abrasive sticks to produce the overlapping between adjacent sticks so that the reciprocation of the tool will produce machining over the entire cylindrical surface. The invention applies particularly to the tool for operating on the external cylindrical surface since the width and spacing at the working surface may readily be maintained throughout the thickness of the abrasive stone.

Accordingly, the main objects of my invention are to provide a tool for machining cylindrical surfaces of workpieces which have abrasive stones which are diagonally disposed to have the stones overlap; to provide an external type of honing tool with a plurality of holders having diagonally disposed stones which nest when extended to a particular diameter with adjacent stones in overlapping relation to each other relative to the planes through the axis of the tool; to provide an external type of honing tool with diagonally disposed abrasive sticks which are adjacently disposed to have the adjacent stones overlapping within a predetermined diameter

2

range and having means for adjusting the abrasive stones within said range; and in general to provide an external type of honing tool which completely machines an external surface when the hone is moved in reciprocation, all of which is simple in construction and positive of operation.

Other objects and features of novelty of my invention will be either specifically pointed out or will become apparent when referring, for a better understanding of my invention, to the following description taken in conjunction with the accompanying drawings, wherein:

Fig. 1 is a view in elevation, with parts broken away, illustrating a machine operating a honing tool embodying my invention;

Fig. 2 is an enlarged broken sectional view of the tool illustrated in Fig. 1;

Fig. 3 is a sectional view of the structure illustrated in Fig. 2, taken on the line 3—3 thereof;

Fig. 4 is a sectional view of the structure illustrated in Fig. 2, taken on the line 4—4 thereof; and

Fig. 5 is a perspective view of a stone and stone holder employed in the tool illustrated in Fig. 2.

In Fig. 1, I have illustrated a workpiece 10 in the nature of a piston, the outer surface of which is to be machined by an external type of honing tool 11 suspended on a shaft 12 mounted in a housing 13 which is reciprocated. The housing is supported on a piston rod 14 mounted on the end of a piston 15 which is disposed in a cylinder 16. The shaft 12 has a gear 17 keyed thereto within the housing 13 and mated with a pinion 18 within the housing which is driven by a spline shaft 19. The housing is guided in its path of reciprocation by a rod 21 over which an arm 22 on the housing slides.

Fluid is admitted to one or the other end of 40 the cylinder through a solenoid operated valve 23, the solenoid of which is controlled by an electrically operated time switch 24. A motor 25 drives through a clutch 26 the spline shaft 19 to produce the rotation of the tool 11. A solenoid 27 is connected to the clutch 26 for interrupting the rotation of the tool after a predetermined time of operation controlled by the time switch 28.

In operation, the housing 13 and tool 11 are reciprocated to have the honing sticks of the tool 11 pass over the workpiece a sufficient amount to permit the expansion of the stones to occur within the working range of the tool. This is accomplished by the engagement of a projection 55 29 on the arm 22 with the cam block 31 of a

valve 32 to maintain the valve in open position. At the same time the motor 25 is energized to rotate the tool 11 for a time controlled by a time switch 28. Upon the operation of the time switch 28, the clutch 26 interrupts the operation of the tool rotation and the operation is continued in reciprocation only. During the rotation of the tool, the stones were worn to the shape of the cylinder so that during the reciprocating cycle the honing will occur throughout the cylindrical surface and parallel to the axis of the work-piece. This produces finish marks on the surface parallel to the axis which conform to the marks which would appear on the surface after the surface had been "worn in" a considerable length of time.

The tool for producing this operation and finish is illustrated in Figs. 2 to 5, inclusive, wherein a body 34 of cylindrical shape is provided with an inner circumferential rib 35 at the top and bottom having a plurality of slots 36 for receiving the ends 37 of the stone carriers 38. A pair of spring rings 39 bias the carriers radially outwardly from the tool axis. A plurality of pins 41 extend through the body 34 in engagement with the rear face of the carriers 38. The outer ends of the pins engage cam surfaces 42 provided on individual cam elements 43. Springs 44 are employed for moving the cam elements 43 upwardly to thereby permit the movement of the stone carriers outwardly when urged by the springs 39.

An outer sleeve 45 encompasses the body and the cam elements and forms an annular cylinder 46 in which an annular piston 47 is disposed in engagement with the upper ends of the cam elements 43. An annular channel-shaped gasket 48 provides a seal for the piston. An annular sleeve 49 is mounted on the body 34 retained in position by a pair of nuts 51. A conduit 52 delivers oil or other fluid from the valve 33 to the annular ring 49 and then to the cylinder 46.

Each of the stone carriers 38 is provided with a stone 54 which is rhomboidal in shape and preferably having an arcuate face. By having the sides parallel the gap between the stones will not vary when the faces are adjusted to a particular diameter and to larger or smaller diameter than the particular diameter for which the tool was constructed. This variation in diameter, however, will be limited to the degree of slope provided to the abrasive stone which controls the amount of overlap produced thereby.

After the tool has been set to a predetermined diameter, a tool similar to that for dressing internal surfaces referred to in the above-mentioned co-pending application is employed for dressing the stones to cylindrical shape on the particular diameter selected. Thereafter the tool may be employed as indicated hereinabove to be rotated and reciprocated relative to a work-piece for producing a honing operation and thereafter reciprocated without being rotated for producing a finished surface with the finish

marks disposed parallel to the axis of the surface.

While I have described and illustrated but a single embodiment of my invention, it will be apparent to those skilled in the art that various changes, omissions, additions and substitutions may be made therein without departing from the spirit and scope of my invention, as set forth in the accompanying claims.

What I claim is:

1. In an abrasive unit for a honing tool, a carrier having a body portion and aligned projecting end portions, the longitudinal axis of the body portion being disposed at an angle to the longitudinal axis of the projecting portions, and a stone secured to said body portion with its axis aligned therewith.
2. In an abrasive unit for a honing tool, a carrier having a body portion and aligned projecting end portions, the longitudinal axis of the body portion being disposed at an angle to the longitudinal axis of the projecting portions, and a stone secured to said body portion with its axis aligned therewith, the projecting face of said stone being of segmental cylindrical form with reference to a center line parallel to the longitudinal axis of the projecting ends of the body portion and which is of helical form relative to the longitudinal axis of the stone.
3. In a stone assembly for a honing tool, a body portion having projecting ends which are in aligned vertical relation, a stone supported by said body portion with the ends disposed in a horizontal plane and the sides disposed at an angle thereto which is other than right angle, the working face of said stone being concave and of segmental cylindrical shape with reference to a vertical axis.
4. An abrasive element for a honing tool which is substantially square in cross section with one side having a concave segmental cylindrical face, the axis of which is disposed at an angle to the longitudinal center line of the abrasive element.
5. An abrasive element of elongated rhomboidal shape having one elongated face of concave segmental cylindrical form, the axis of said cylinder being disposed at an angle to the edges of said face.
